DISPLAY SIGN CONTROL MECHANISM

St. George Lafitte, Summit, N. J., assignor to
 Federal Telegraph Company, Newark, N. J., a
 corporation of California

Application December 9, 1938, Serial No. 244,798

9 Claims. (Cl. 40—36)

My invention relates to display devices and more particularly to improvements in sign mechanisms and control arrangements for advancing sequentially a series of units around a closed conveyor circuit.

In a known form of conveyor system a plurality of separate units are carried around a closed circuit one at a time. When each unit has almost completed the circuit the conveyor chain releases the unit and the latter is advanced from this point to a point from which it is again picked up for another circuit around the conveyor, by means of suitable pusher elements operating with a pawl and ratchet movement.

It is an object of my invention to provide a suitable latching and escapement mechanism for controlling conveyor units of the type mentioned and releasing them for travel around a circuit.

In the usual forms of display devices utilizing a conveyor of the type outlined above, only one display window may be provided without a considerable complication of the control mechanism and increase in power for driving the arrangement. By means of a control arrangement in accordance with my invention display posters may be simultaneously shown on a plurality of separate faces of the display device without substantial increase in power and with but a simple modification of mechanism ordinarily used for a single display.

In accordance with another feature of my invention a conveyor carried by a chain, itself serves to trip a release mechanism to release the succeeding unit for travel around the circuit, and also operates means to advance a pusher pawl mechanism so as to advance the other units along the circuit over a portion of the circuit not traversed by the carrying chain or belt.

In accordance with another feature of my invention, I provide a track for guiding the conveyor units over portions of the circuit in advance of the pulleys or sprocket wheels so that any looseness in the driving belt or chain will not interfere with the positive action of the device, and the strain of operating the mechanism is not carried by the belt or chain of the conveyor.

Other objects of my invention will become clear from a complete consideration of the description made in connection with the accompanying drawings, in which

Fig. 1 shows a schematic arrangement of a conveyor system in accordance with my invention,

Fig. 2 illustrates partly in section and partly broken away, a display device in accordance with

my invention showing the latching and tripping mechanism in one position.

Fig. 3 is a plan view partly in section and broken away of the embodiment of my invention disclosed in Fig. 2, in which the latching and closure mechanism are in their alternative positions.

Fig. 4 illustrates in plan view a section of chains and a conveyor element for use in the arrangement illustrated in Figs. 2 and 3, and

Fig. 5 is a side elevation of Fig. 4.

Turning now to Fig. 1, 11 represents a chain or belt to which is attached a conveyor element indicated at 12. This conveyor element is provided with a projection 13 which is adapted to carry around therewith, one of a plurality of carrier units 10. Each of these units 10 may be any type of member which is to be advanced around the closed conveyor circuit. For example, each unit 10 may be formed as a channel-shaped member and may have attached to it one end of a display poster, which posters are successively carried around the circuit so as to sequentially display various advertising posters. In the arrangement shown in Fig. 1, a plurality of these units are confined between the latching element 21 of the toggle latch assembly 20, and the pusher lever 41 of the push latch lever assembly 40. Toggle latch arrangement 20 and the push latch lever assembly 40, are cooperatively linked together by means of a connecting link 50. Lever 42 is pivoted at fixed pivot 43 and at its far end push lever or pawl 41 is pivoted thereto. A tension spring 44 is provided to maintain lever 41 pivoted outwardly so that the pushing surface of lever 41 will be maintained in proper position to contact with a unit 10. A latching arm 45 pivoted at fixed pivot 46 and tensioned by a suitable spring 47, extends outwardly into the path of the approaching unit 10, as shown in the drawings. Springs 44 and 47 are relatively light so that lever 41 and latching arm 45 may be readily displaced inwardly out of the path of units 10, by roller 15 carried by conveyor element 12, as this element passes the push lever latch assembly. Link 50 is pivoted on lever 42 at a point intermediate fixed pivot 43 and lever 41, so that in the solid line position the long arm of lever 42 is moved toward the right, as seen in the figure and in the dotted line position the long arm of lever 42 is moved to the left.

When link 50 is moved to the left, the toggle latch assembly is also moved into the solid line position as shown in Fig. 1. This assembly comprises the pivoted lever 22 to which at a point

50

55

- intermediate its ends is pivoted link 50. A toggle link 23 is pivoted at a fixed point intermediate the two positions of arm 22 and is provided with a compression spring 24, so that lever 22 upon passing the center of its rotation will tend to immediately occupy either of two positions, as shown in the solid lines or the dotted lines, Fig. 1. Lever 22 carries pivoted thereto a vertically movable stop member 25. In the position shown in solid lines in Fig. 1, stop member 25 is withdrawn from its latching relationship with respect to the units 10. The latching member 21, is pivoted at a fixed point 26 and is provided at one end with a sliding connection 27, so that the projecting latching end 28 of lever 21 is moved into or out of the path of the units 10 in accordance with the position of stop member 25. As shown in the solid lines of Fig. 1, the auxiliary latching member or stop 21 is in its raised position and accordingly the projecting end 28 of latching member 21 is protruding into the path of unit 10, so that these elements are maintained in fixed position between latching element 21 and push lever 41.
- 25 In the solid line position conveyor element 12 is at its position just before it passes control lever 42. As the chain or belt continues to progress, conveyor element 12 is carried around thereby and the associated carrier unit 10 is carried along with it. When the conveyor element 12 reaches a position so that the carrier unit 10 is disposed immediately above the latching arm 45, the chain or belt moves away from the unit so that projection 13 no longer cooperates therewith and the unit is left in this position. Latching arm 45 projects into the opening in unit 10 to hold it in position during later return or ratchet movement of push lever 41.
- The conveyor element 12 continues on around the circuit eventually reaching a point adjacent the toggle latch assembly 20. Upon reaching a point opposite the toggle latch assembly, roller 15 on conveyor element 12 pushes against the outer end of lever 22 or a suitable projection thereon 45 rocking the lever to its dotted line position. This movement of lever 22 moves auxiliary stop member 25 outwardly into the opening of the unit 10 next to the end to prevent displacement of these units. As soon as lever 22 reaches a point slightly past its dead center, spring 24 serves to force it completely into its dotted line position, moving link 50 to the right and rocking control lever 42 to the left, into its dotted line position as shown in Fig. 1. The outward movement of stop member 25 rocks latching arm 21 moving its latching end 28 out of the path of the units 10. Projection 13 on conveyor element 12 contacts with the forward one of the units 10 so that this element is picked up for travel around the circuit.
- 60 The movement of control lever 42 to the left withdraws push lever 41 to the right so that the pusher end of this lever is located at a point just beyond the outer edge of the carrier unit 10 which has most recently been deposited at this point.
- 65 During the movement of push lever 41 to the right the latching arm 45 serves to hold the outer unit 10 from being dragged back with the push lever.
- As conveyor element 12 continues further around the circuit it finally reaches a position 70 such that roller 15 is brought to bear against the end of control lever 42 serving to again force this lever toward the right. Control lever 42 upon moving pushes on link 50 rocking lever 22 back and when it has moved a sufficient distance to rock lever 22 again to a position beyond dead

center, toggle link arm 23 and compression spring 24 serve to suddenly rock lever 22 to its solid line position, moving lever 42 to its extreme right hand position, advancing push lever 41 towards the left and simultaneously withdrawing stop member 25 from its holding position in the unit 10 and operating latching member 21 to position so that its projecting end 28 is again positioned in the path of these units 10. In this position the apparatus is returned to the solid line position of Fig. 1. The cycle is then repeated, thus in turn carrying each of the units 10 around the circuit in succession.

It is evident that the arrangement of my invention may be utilized for any system in which it is desired to successively carry elements around a particular circuit. One particular application of the system is for the use of interchangeable display signs such as are used commonly for displaying advertising matter. In such a system each of the units 10 may be so arranged that an advertising display folder is attached to the leading edge thereof. Thus as each of the elements is removed from its rest position a new advertising sign display is presented to view and the one previously removed is returned around the circuit to be again shown in its turn.

It is evident that with an arrangement such as shown in Fig. 1 by providing similar control and latching arrangements about two or more faces of the display arrangement, each of the faces may be used to simultaneously display separate signs. In the arrangement as one unit is removed from the chain adjacent one face it is deposited in the group adjacent another face of the device and a unit on the far end of the group adjacent this second face is then removed to the succeeding face of the system and so on around the circuit.

In Figs. 2 and 3 is illustrated a preferred form of my invention applied to a display sign in which two faces of the sign are utilized for display purposes. In these figures the various parts corresponding to those shown in Fig. 1 carry corresponding reference characters.

The display sign structure comprises the plate or base elements 100, the metallic end walls 101 and the transparent display faces 102-103. Mounted on shafts supported between the base plates 100 are provided sprocket wheels 105 for driving the chain 11. Connected at one point in the chain is provided the conveyor element 12. The particular construction of this conveyor element may be more clearly seen by reference to Figs. 4 and 5 which illustrate a portion of the sprocket chain and the carrier mechanism. The chain is composed of a plurality of links 400 and fastened between two of these links are provided the carrier elements 12 having a projecting conveyor portion 13. On a pin 401 projecting through the elements 12 are mounted the rollers 15 and this pin 401 also serves as a connection for one of the links 400. On the other end of conveyor elements 12 is provided a second pin 402 which serves as a means for connecting the other links 400 of the sprocket chain to the carrier elements. The sprocket chain 11 is driven around its closed circuit by means of the sprocket wheels 105.

The carrier units 10, each of channel shape, are carried around the circuit by means of the conveyor elements 12, the ends of the units maintained in the groove 110 are provided in base plate 100 and a similar groove in the upper cover plate, not shown. It should be understood that similar latching mechanisms may be provided

near the top and bottom of the carrier units 10 to properly control these elements. In the position shown in Fig. 2 the carrier units 10 which are positioned to display signs through the face 102 of the display device are retained in their fixed position between latching elements 21 of the toggle latch assembly and push lever 41 of the push latch assembly. In this position toggle link 23 is moved to its extreme left position and the control lever 42 is moved to its position to the right. At the same time the control levers 42' for controlling the conveyor units on the front surface of the display device 103 are in a corresponding position as can be seen in part by reference to control levers 42' and the associated push levers 41', connecting link 50' and latching lever 45'.

Conveyor element 12 is just passing the control lever 42 preparatory to depositing conveyor unit 10 at a point just back of push lever 41'.

In order to control the movement of the auxiliary latching member 25, I provide a plate 115 with a slot 116 therein through which pin 130 carried by member 25 may be guided. Pin 130 also serves as a guide for the sliding connection 27 provided on lever 21.

As conveyor element 12 proceeds around the circuit it operates the toggle latch assembly associated with the face 103 of the display device to force control lever 42' to the right, releasing another carrier unit 10 which is then carried to and deposited at a point immediately adjacent the units held by push lever 41. Proceeding further, conveyor element 12 reaches a point at which projection 13 enters the channel of carrier unit 10 adjacent stop element 21. Simultaneously roller 15 contacts projection 30 on lever 22 rocking lever 21 to release end unit 10, moving auxiliary latching member 25 downwardly into the channel opening of succeeding unit 10 and returning push lever 41 to the left into the position illustrated in Fig. 3.

As shown in Fig. 3, control lever 42 has been moved to the left against stop pin 107 so that the push lever 41 is now in a position to the right of the row of units 10. Latching lever 45 held the last unit from being dragged back by lever 41. The toggle latch assembly is in its alternative position with auxiliary latching member 25 projected into the opening or channel of the end unit 10 and main latching lever 21 removed from the path of the units. Conveyor element 12 has reached a position such that roller 15 is just beginning to push control lever 42 toward the right. Movement of lever 42 a short distance serves to rock lever 22 sufficiently to snap toggle latch assembly 20 into the position shown in Fig. 2, moving lever 42 all the way to its other position. This cycle of operation is repeated, depositing one of the units 10 on face 103 of the display sign, picking up another unit from the end of the group displayed on face 103 and carrying it around to face 102, depositing it there and then picking up another unit, bringing it around to face 103. This cycle is repeated continuously, displaying in turn on the separate faces of the display device each of the several display signs.

The sprocket chain tends to follow the sprocket wheel around at the point it leaves the wheel, tending to remove projection 13 on conveyor element 12 from the channel of the conveyor unit at these points. To overcome this difficulty I provide track members 140 arranged between the two wheels 105 at the ends of the device, Figs. 2 and 3. This track element bears against roller 15 on the

conveyor element 10 so that the chain may not be displaced inwardly while the conveyor element is passing this point. Likewise, I provide a track 141 along the conveyor chain on the faces of the display device so as to prevent the chain from following around the wheel and removing the conveyor element 12 from units 10. Similar tracks are provided at both ends of the system and on both faces thereof. Since the views illustrating the apparatus are fragmentary, the tracks are not shown complete for the system. It will be understood, however, that the device may be made entirely symmetrical so that the front and rear faces of the display device are exactly alike except for the reversal of position of the latching arrangements.

While I have illustrated a preferred embodiment of my invention with the control levers and trip latch arrangements related to opposite sides, this arrangement is not essential to the operation of the invention. It is clear that by changes in the design of the levers they may extend into the path of an element carried on conveyor chain 11, on the same face upon which the display posters and push latch assembly is arranged. The assembly may be so arranged as to operate the latches and pawls during the passage of the carrier element about any suitable face of the display device. Furthermore, any suitable variation in the design of the elements utilized in the system can be readily worked out by those skilled in the art, as long as intermittently operated latching and push-pull mechanisms to advance the elements around the system sequentially are provided. For example the pick-up and tripping members need not be carried by the same part of the conveyor chain but may constitute separate members spaced apart thereon. The essential feature of this arrangement is that the release of a unit and the pick-up of the unit for movement around the travel portion of its path be properly timed so that the unit will not be permitted to move out of alignment.

Independent means may likewise be used to operate the pawl although it is preferable to have this pawl and the escapement latch interlock since on its forward stroke the units in the storage portion must be free to move. Moreover, it is clear that the return of the escapement latch and the pawl for advancing the units over the storage portion of the path need not be operated by an element carried on the conveyor chain but may be accomplished by cams arranged so as to operate subsequent to the release of one unit therefrom.

While I have described a particular embodiment of my invention with reference to the accompanying drawings, this description is not to be considered as a limitation upon the scope of my invention but merely as an illustration thereof. What I consider as my invention and desire to protect is embodied in the accompanying claims.

What I claim is:

1. A display device comprising a plurality of display carrying units, means forming a closed path including a storage portion and a travel portion about which said units are adapted to be advanced, a flexible conveyor element movable about a closed circuit, a pick-up member on said conveyor element for carrying one of said units around said travel portion of said path, stop means and a pawl means extending into said path for restraining the others of said units within said storage portion, means for causing said pick-up member to deposit said one carried unit

- in said storage portion adjacent said pawl, a tripping member on said conveyor element, means operative by said tripping member for removing said stop means from said path and releasing one 5 of said units, means operated by releasing movement of said stop means for moving said pawl back of said deposited unit, means for causing said pick-up member to pick up said released unit in timed relation with said unit's release, 10 and means operative to subsequently return said stop means in said path and advance said pawl to push said stored units forward against said stop.
2. A display device comprising a plurality of 15 display carrying units, means forming a closed path including a storage portion and a travel portion about which said units are adapted to be advanced, a flexible conveyor element movable about a closed circuit, a pick-up member on said 20 conveyor element for carrying one of said units around said travel portion of said path, stop means and a pawl means extending into said path for restraining the others of said units within said storage portion, means for causing said pick-up 25 member to deposit said one carried unit on said storage portion adjacent said pawl, a tripping member on said conveyor element, means operative by said tripping member for removing said stop means from said path and releasing one of 30 said units, means operated by releasing movement of said stop means for moving said pawl back of said deposited unit, means for causing said pick-up member to pick up said released unit in timed relation with said unit's release, and means operated by said tripping member to subsequently 35 return said stop means into said path and advance said pawl to push said stored units forward against said stop means.
3. A display device comprising a plurality of 40 display carrying units, means forming a closed path including a storage portion and a travel portion about which said units are adapted to be advanced, a flexible conveyor element movable about a closed circuit, a pick-up member on said conveyor element for carrying one of said units around said travel portion of said path, escape- 45 ment means for restraining said units in said storage portion of said path, means causing said pick-up member to deposit said one unit in said storage portion of said path, a tripping member on said conveyor element, means operative by said tripping member for moving said escapement means to release one of said units, stop means operative in response to releasing operation of 50 said escapement means to hold the unit adjacent said released unit from movement, and means for causing said pick-up member to pick up said released unit in timed relation to said release for movement about said travel portion.
- 55 4. A display device comprising a plurality of display carrying units, means forming a closed path including a storage portion and a travel portion about which said units are adapted to be advanced, a flexible conveyor element movable about a closed circuit, a pick-up member on said conveyor element for carrying one of said units around said travel portion of said path, stop means and a pawl means extending into said path for restraining the others of said units within said 60 storage portion, means for causing said pick-up member to deposit said one carried unit on said storage portion adjacent said pawl, auxiliary latching means for holding said deposited unit in position, a tripping member on said conveyor element, means operative by said tripping member for removing said stop means from said path and releasing one of said units, means operated by releasing movement of said stop means for moving said pawl back of said deposited unit, holding means operative upon releasing movement of said stop means for holding the next adjacent unit from movement, means for causing said pick-up member to pick up said released unit in timed relation with said unit's release, and means operative by said tripping member to subsequently return said stop means into said path, release said holding means and advance said pawl to push said stored units forward against said stop.
- 65 5. A display device comprising a plurality of display carrying units, means forming a closed path including a storage portion and a travel portion about which said units are adapted to be advanced, a flexible conveyor element movable about a closed circuit, a pick-up member on said conveyor element for carrying one of said units around said travel portion of said path, stop means and a pawl means extending into said path for causing said pick-up member to pick up said released unit in timed relation with said unit's release, and means operative to subsequently return said stop means into said path, advance said pawl to push said stored units forward against said stop.
- 70 6. A display device comprising a plurality of display carrying units, means forming a closed path including a storage portion and a travel portion about which said units are adapted to be advanced, a flexible conveyor element movable about a closed circuit, a pick-up member on said conveyor element for carrying one of said units around said travel portion of said path, stop means and a pawl means extending into said path for restraining the others of said units within said storage portion, means for causing said pick-up member to deposit said one carried unit on said storage portion adjacent said pawl, auxiliary latching means for holding said deposited unit in position, a tripping member on said conveyor element, means operative by said tripping member for removing said stop means from said path and releasing one of said units, means operated by releasing movement of said stop means for moving said pawl back of said deposited unit, holding means operative upon releasing movement of said stop means for holding the next adjacent unit from movement, means for causing said pick-up member to pick up said released unit in timed relation with said unit's release, and means operative by said tripping member to subsequently return said stop means into said path, release said holding means and advance said pawl to push said stored units forward against said stop.
- 75 7. A display device comprising a plurality of display carrying units, means forming a closed path including a storage portion and a travel portion about which said units are adapted to be advanced, a flexible conveyor element movable about a closed circuit, a pick-up member on said conveyor element for carrying one of said units around said travel portion of said path, stop means and a pawl means extending into said path for restraining the others of said units within said storage portion, means for causing said pick-up member to deposit said one carried unit on said storage portion adjacent said pawl, auxiliary latching means for holding said deposited unit in position, a tripping member on said conveyor element, means operative by said tripping member for removing said stop means from said path and releasing one of said units, means operated by releasing movement of said stop means for moving said pawl back of said deposited unit, holding means operative upon releasing movement of said stop means for holding the next adjacent unit from movement, means for causing said pick-up member to pick up said released unit in timed relation with said unit's release, and means operative by said tripping member to subsequently return said stop means into said path, release said holding means and advance said pawl to push said stored units forward against said stop.

units around said travel portion of said path, stop means and a pawl means extending into said path for restraining the others of said units within said storage portion, means for causing said pick-up member to deposit said one carried unit on said storage portion adjacent said pawl, auxiliary latching means for holding said deposited unit in position, a tripping member on said conveyor element, means operative by said tripping member for removing said stop means from said path and releasing one of said units, means for moving said pawl back of said deposited unit, holding means operative upon releasing movement of said stop means for holding the next adjacent unit from movement, means for causing said pick-up member to pick up said released unit in timed relation with said unit's release, and means operative to subsequently return said stop means into said path, release said holding means and advance said pawl to push said stored units forward against said stop in timed relation.

8. A display device comprising a plurality of display carrying units, means forming a closed path including a storage portion and a travel portion, about which said units are adapted to be advanced, a flexible conveyor element movable about a closed circuit, a pick-up member on said conveyor element for carrying one of said units around said travel portion of said path, escapement means for restraining said units in said storage portion of said path, means causing said pick-up member to deposit said one unit in said storage portion of said path, a tripping member on said conveyor element, means operative by said tripping member for moving said escape-

ment means to release one of said units, means for causing said pick-up member to pick up said released unit in timed relation to said release for movement about said travel portion, and guiding means arranged about said travel portion of said path for maintaining said pick-up member in co-operating relation with said carried unit over said travel path. 5

9. A display device comprising a plurality of display carrying units, means forming a closed path comprising a plurality of storage portions and a plurality of travel portions about which said units are adapted to be advanced, a flexible conveyor element movable about a closed circuit, a pick-up member on said conveyor element for carrying one of said units around said travel portions of said path, escapement means for restraining said units in each of said storage portions of said path, means for causing said pick-up member to deposit said one unit in one of said storage portions of said path, a tripping member on said conveyor element, means operative by said tripping member for moving said escapement means adjacent said one storage portion to release one of said units, stop means operative 25 in response to releasing operation of said escapement means to hold the unit adjacent said released unit from movement, means for causing said pick-up member to pick up said released unit in timed relation to said release for movement about the succeeding travel portion, and to deposit it at the next storage portion for successively depositing and removing units from each of said storage portions. 30
